UNITED STATES PATENT OFFICE.

WILLIAM S. MCKENNA, OF PITTSBURG, PENNSYLVANIA, ASSIGNOR OF ONE-HALF TO JOSEPH W. KEFFER, OF SAME PLACE.

METALLURGICAL FURNACE.

SPECIFICATION forming part of Letters Patent No. 576,323, dated February 2, 1897.

Application filed June 22, 1896. Serial No. 596,525. (No model.)

To all whom it may concern:

Be it known that I, WILLIAM S. MCKENNA, a resident of Pittsburg, in the county of Allegheny and State of Pennsylvania, have invented a new and useful Improvement in Metallurgic Furnaces; and I do hereby declare the following to be a full, clear, and exact description thereof.

My invention relates to furnaces for heating what are commonly called "pairs" and "packs," in connection with the manufacture of sheet-iron.

The object of my invention is to construct such a furnace with flues arranged in such a manner as to obtain the greatest amount of heat for the amount of fuel used, and largely reduce the cost of manufacture. My invention therefore comprises certain details of construction, all of which will be fully hereinafter set forth and claimed.

To enable others skilled in the art to make and use my invention, I will describe the same more fully, referring to the accompanying drawings, in which—

Figure 1 is a longitudinal vertical section of my improved furnace. Fig. 2 is a section on the line 2 2, Fig. 1. Fig. 3 is a front view, and Fig. 4 is a section on the line 4 4, Fig. 2.

Like letters of reference indicate like parts in each.

In the accompanying drawings the letter *a* designates the walls of the furnace, which are constructed of brick, and which may be braced and held together in any suitable manner. At one end of the furnace is a pair-heating chamber *b*, which has the floor *b'*, adapted to receive the metal. The pair-heating chamber is provided with the charging-doors *b²* and the air-inlet *b³*. This air-inlet *b³* is provided with the swinging door *b⁴*, said door having the chains *b⁵* connected thereto, which pass over pulleys *b⁶*, said chains having the weights *b⁷* attached thereto. Leading from the bottom of the pair-heating chamber are the flues *c*, said flues extending up and communicating with a common flue *c'*, extending along the top of the furnace and communicating with the chimney *d*. Beneath the floor *b'* of the pair-heating chamber *b* is the air-heating chamber *e*, which is in direct communication with the atmosphere.

At the other end of the furnace is the sheet-heating chamber *f*, said chamber having the inclined floor *f'*, made up of tiles of suitable dimensions. The sheet-heating chamber *f* is provided with the charging-door *f²*, adapted to slide up and down in suitable guides, and which has the chains *f³* connected thereto passing up over the pulleys *f⁴*, said chains having the weights *f⁵* attached thereto. The floor *f'* of the sheet-heating furnace is supported by the partitions *g*, which divide the space beneath said floor into separate chambers *g'*. These chambers *g'* are in communication with the sheet-heating chamber *f* through the openings *g²* adjacent to the charging-door *f²*. The opening *h*, leading to the several chambers *g'* below the floor *f'* of the sheet-heating chamber, is provided with the door *h'*, which is hinged at the top and adapted to swing from that point. Leading from the space below the floor *f'* and communicating with the several chambers *g'* are the flues *i*, which pass up through the walls of the furnace and communicate at their upper ends with the chimney.

Intermediate of the pair-heating chamber *b* and sheet-heating chamber *f* is the fire-chamber *k*, said fire-chamber being provided with the grate-bars *k'*, beneath which is the ash-pit *k²*. The doors *k³* close the opening leading to the ash-pit *k²*. The ash-pit *k²* is also provided with the air-inlet *k⁴*, and the plate *k⁵*, having openings *k⁶* therein, permits air to enter above the grate-bars. The fire-chamber *k* is provided with a suitable stoking-hole *l*. A fire-bridge *m* extends up between the fire-chamber and the pair-heating chamber. The fire-chamber *k* is in communication with the pair-heating chamber *b*, and by means of the flue *n* also in communication with the sheet-heating chamber *f*. This flue *n* is formed by the bridge *o*, which separates the fire-chamber from the sheet-heating chamber, said bridge *o* having the forwardly-projecting arch *o'*. The flue *n* is thus formed between the upper face of the arch *o'* and the top of the furnace. This bridge *o* has the air-passage *o²* formed therein, said air-passage being in communication with the flues *p*, which lead from the air-space *e* to said passage, said flues being formed in the side walls of the fur-

nace. In this manner the air which passes through the flues *p* around the fire-box is highly heated, and when discharged from the passage *o*² into the sheet-heating chamber at 5 the point where the products of combustion coming through the flue *n* meet said highly-heated air a very high heat in the sheet-heating chamber results, while at the same time a more perfect combustion is obtained.

10 The steam-pipe *r* has the branches *r'* *r*² *r*³ connected thereto. The branch pipes *r*, which are located within the flue *c'*, when emitting steam create a draft through the pair-heating chamber, said branch pipes having the ends 15 *r*⁴ longitudinal of said flue *c'*, and with the outlets in the direction of the chimney *d*. The branch pipes *r*², projecting straight down within the flue *c'* when emitting forth steam, act as a damper and practically close off the 20 draft through the pair-heating chamber to the chimney *d*. The branch pipe *r*³ has the vertical end *r*⁵, which projects up within the chimney, and when emitting forth steam creates a draft through the sheet-heating chamber 25 and up the flues *i* to the chimney *d*. These branch pipes are all provided with suitable valves *s*.

When the furnace is in use, it is operated in 30 the following way: Fire is started in the fire-chamber, and when the furnace has been raised to the proper heat both the pair-heating chamber and the sheet-heating chamber may be charged with bars and sheets, respectively. It is customary to allow the bars or 35 billets in the pair-heating chamber to "soak," as it is commonly termed, until they have been raised to a high temperature. To accomplish this, the valve leading to the branch pipes *r*² is opened, so that said branch pipes emit the 40 steam into the flue *c'*. This cuts off the draft and the heat is retained within the pair-heating-chamber until the bars or billets have been raised to the proper temperature. The steam is then shut off from the branch pipes *r*² and 45 the valves of the branch pipes *r'* are then opened to allow the steam to escape through the ends *r*⁴. This creates a draft through the pair-heating chamber *b* by means of the flues *c c'* to the chimney *d*. As the products of combustion from the fire-chamber pass over the bridge-wall *m* they are sent to the top of the pair-heating chamber and are then compelled 50 to descend to the bottom thereof in order to escape by the flue *c*. In this manner the heat 55 is allowed to circulate thoroughly throughout the chamber before it makes its escape. As the heat ascends through the flue *c* it passes into the flue *c'*, which is directly over the pair-heating chamber and is only separated from the

same by the roof of said chamber. In this 60 way the escaping heat is utilized to further heat the pair-heating chamber. At the same time the sheet-heating chamber *f*, having been charged with packs, the steam is allowed to escape from the ends *r*⁵ of the pipes *r*³. This 65 creates a draft through the sheet-heating chamber *f*, the course of the draft being from the fire-chamber up over the wall *o*, through the flue *n* into the chamber *f*, thence down through the openings *g*² into the flues *g*', and 70 thence up through the flues *i* to the chimney *d*. Highly-heated air is constantly admitted to the sheet-heating chamber *f* by means of the air-flues *p*, which communicate with the passage *o*² of the bridge *o*. In this way the 75 products of combustion coming from the fire-chamber and the highly-heated air meet at about the middle of the sheet-heating chamber and create an intense heat. The slanting hearth of the sheet-heating chamber and 80 the projecting arch *o*' act to form a chamber which is deep at the inner end of the sheet-heating chamber, but which has a contracted opening due to the slanting of the hearth. In this manner the highly-heated products of 85 combustion are held within the sheet-heating chamber before they are permitted to escape through the openings *g*². The bridge-wall *o* and the arch *o*' become highly heated and the 90 heat is radiated onto the packs, so that in this way all the heat is utilized. Air may also be admitted to the fire-chamber through the opening *k*⁴, said air passing up through the grate-bars and also up through the openings *k*⁶. 95

What I claim as my invention, and desire to secure by Letters Patent, is--

A furnace for heating metals having a pair-heating chamber and a sheet-heating chamber, a fire-chamber intermediate of said chambers, bridge-walls separating said fire-chamber from said chambers, an arch extending into the sheet-heating chamber from the upper end of the bridge-wall separating said chamber from the fire-chamber, said pair-heating chamber having a flue leading from the bottom thereof to a flue just above the top of said furnace, said pair-heating chamber and sheet - heating chamber communicating with a common chimney, substantially as set forth. 100 105 110

In testimony whereof I, the said WILLIAM S. MCKENNA, have hereunto set my hand.

WILLIAM S. MCKENNA.
